United States Patent Office.

MORTON E. CONVERSE, OF RINDGE, NEW HAMPSHIRE, AND ABEL T. AHERTON, OF LOWELL, MASSACHUSETTS.

Letters Patent No. 78,264, dated May 26, 1868; antedated May 13, 1868.

IMPROVEMENT IN THE MANUFACTURE OF PYROLIGNEOUS ACID.

The Schedule referred to in these Letters Patent and making part of the same.

TO ALL WHOM IT MAY CONCERN:

Be it known that we, MORTON E. CONVERSE, of Rindge, in the county of Cheshire, and State of New Hampshire, and ABEL T. AHERTON, of Lowell, in the county of Middlesex, and State of Massachusetts, have invented new and useful Improvements in the Manufacturing of Pyroligneous Acid, Pyroxylic Spirit, Wood-Tar, &c.; and we do hereby declare that the following is a full and exact description thereof, reference being had to the accompanying drawings, and to the letters of reference marked thereon.

The nature of our invention consists in providing for kilns, flue-tubes, and discharge-pipes, arranged in one or more rows, and on one or more sides of the kiln.

Their object being to save and collect the products of the destructive distillation of wood in the kiln, consisting of pyroligneous acid, pyroxylic spirit, wood-tar, &c.

To enable others skilled in the art to make and use our invention, we will proceed to describe its construction and operation.

Figure 1 represents a plan of a kiln, with our improved arrangement of flue-tubes and discharge-pipes attached.

Figure 2 represents an end elevation of the same.

Similar letters in the different figures indicate corresponding parts.

a represents the kiln, which may be made of brick, stone, or metal, of the required form and shape. *b* is the lower charging-door, through which and into the kiln *a* are placed or charged the heavier and larger pieces of wood to be carbonized. *c* is the upper charging-door, through which are charged or placed the smaller and lighter pieces of wood. It also enables the operator to completely pack and fill the remaining space in the kiln *a*, which otherwise could not be filled. *d* is the door which closes the aperture through which fire is communicated to the wood in the top of the kiln *a*. *e e* are draught-holes, which supply the requisite quantity of air for feeding the fire, these holes being located near the bottom and on all sides of the kiln *a*, if occasion requires. *f f* are the upper flue-tubes, *g g* the lower flue-tubes, the office of the tubes *f f* being to receive and convey the vapors, smoke, &c., during the process of carbonizing the wood which is placed above them, the object of the flues *g g* being to receive and convey the vapors, smoke, &c., during the process of carbonizing the remaining portion of wood. *h h* are the discharge-pipes; *i i* and *i' i'* the dampers.

The kiln *a* being prepared of the required size, form, and shape, with its doors *b*, *c*, and *d*, and draught-holes *e e*, the tubes *f f* and *g g*, "when two rows are required," with their dampers *i i* and *i' i'*, connect with the kiln *a*, on one or more sides, at the required distances apart, and to the discharge-pipes *h h*. A layer of large logs is then loosely placed on the bottom, in the inside of the kiln *a*, for the purpose of forming a support, upon which is placed the wood to be carbonized.

These logs are also intended to prevent the draught-holes *e e* from being closed during the carbonization of the wood. The kiln *a* is then packed loosely, full to the top, with wood. A fire is then kindled on top of the wood, through the aperture, and the door *d* closed.

The dampers *i i*, in the flue-tubes *f f*, being opened, and the dampers *i' i'*, in the flue-tubes *g g* closed, the vapors, smoke, &c., pass into the tubes *f f*, where they are conveyed into the discharge-pipes *h h*, and then they are conducted into the condenser, through the connecting-pipe *j*.

When the wood becomes carbonized down even with the tubes *f f*, the dampers *i i* are closed, and the dampers *i' i'* in the tubes *g g* opened, otherwise it would create too great a draught, increasing the amount of fire, thus reducing the wood to ashes, and the results sought for not gained.

Thus, by this arrangement, we are not only enabled to produce coal, but to save and collect these several chemical properties, to wit, pyroligneous acid, pyroxylic spirit, wood-tar, &c., which have heretofore been lost.

These same results would be obtained by arching over the bottom of the kiln *a*, and firing up in under this arch, instead of on top of the wood in the kiln *a*, as before described.

We disclaim the kiln *a*, as having long been in common use; but
What we do claim as our invention, and desire to secure by Letters Patent, is—
The application and arrangement of the flue-tubes *ff* and *gg*, in one or more rows, to a kiln, in such a
manner that they will conduct, carry off, and save, the products of destructive distillation of wood, substantially
as described and set forth!

MORTON E. CONVERSE,
ABEL T. ATHERTON.
